UNITED STATES PATENT OFFICE

ALFRED REHM, OF STUTTGART, GERMANY, ASSIGNOR TO ROBERT BOSCH AKTIENGESELLSCHAFT, OF STUTTGART, GERMANY

ELECTRICAL HEATING DEVICE FOR CURLING TONGS

Application filed November 18, 1929, Serial No. 408,065, and in Germany November 24, 1928.

The present invention relates to electrically heated curling tongs.

In curling tongs having a built-in heating resistance, the temperature of the curling tongs is usually regulated by an adjustable series resistance, which is housed in a container secured to the wall. This series resistance is disadvantageous as it consumes considerable power. Also the adjustment through the series resistance does not always correspond to the actual temperature of the curling tongs when in use, as this is also dependent on the momentary heat delivery of the curling tongs.

According to the present invention a temperature controlled switch is installed in the heating tong element of a curling tongs which can automatically switch the current for the heat resistance off and on as the temperature rises or falls.

One form of construction of the invention is illustrated by way of example in partial section in the accompanying drawing.

Inserted in the hollow heating tong element 1 of a pair of curling tongs is a tube 2 of zinc or other metal of relatively high coefficient of expansion into which an insulated tube 3 is introduced.

Mounted in the upper end of the tube 2 is a rod 4 of quartz glass or the like material of relatively low coefficient of expansion. A heating resistance 5 is wound on the rod 4.

Mounted on the free end of the rod 4 is a boss 6 of iron or other electrical conducting material provided with outer threads on which is screwed an iron sleeve 7. A pin 8 which has a flange-shaped stop 9 and a contact head 10 is disposed within the boss 6 and sleeve 7. The free end of the sleeve 7 is bent over to secure an annular disc 11. A helical spring 7 is tensioned between the flange of the sleeve 6 and the stop 9 of the pin 8 and tends to force the stop 9 against the annular disc 11.

A pin 14 is screwed into a tube-shaped ex-

tension 13 of the tube 2 and carries an insulated contact or bridge 16 through an intermediate insulator 15, the contact being of truncated conical form. A contact spring 17 secured to the end of cylinder 2 but insulated therefrom is adapted for contact with the bridge 16 and is connected to a source of current by means of a lead 18.

The screw pin 14 has a head 20 provided with divisions 19 and the position of the divisions can be read off the end of an indicator 21, secured to the heated tong element 1.

During installation the position of the pin 8 relative to the contact 16 can be adjusted by screwing the collar 7 onto the sleeve 6. One end of the heat resistance 5 is connected to the sleeve 6 and through this to the pin 8; the other end of the heat resistance being attached to a lead 22.

As the temperature of the heating resistance rises the zinc tube 2 expands more than the quartz rod 4. The pin 8 follows the expansion of the zinc rod 2 until the stop 9 abuts against the annular disc 11. If the temperature of the heated tong element rises still further, then the contacts 10 and 16 separate on the further expansion of the zinc rod and the heating resistance is thereby switched off. During the subsequent cooling of the curling tongs the zinc rod 2 again contracts so that the contacts 10 and 16 again touch.

By screwing out the screw pin 14, the position of the contact 16 relative to the contact 10 is altered in such a way that the opening of the pair of contacts is effected and a lower temperature than formerly is provided. The position of the screw pin 8 can be read off by means of the divisions 19 gauged according to the temperatures.

The form of construction shown by way of example has the advantage that the heat acting on the wall of the heated tong element influences the heat switch directly and the heat arising during the practical use of the curling tongs is thereby controlled.

In a modified form of construction the tube 2 may itself form a heated tong element.

Again a differently constructed heat switch can be installed in the curling tongs, for example a switch working with a bimetallic spring.

I claim:

1. An electrical heater for curling tongs comprising a hollow casing, a heating resistance within said casing, two longitudinal members of different heat coefficient of expansion connected together at one end, a pair of switch contact elements in series with said resistance each contact element being 10 connected to the free end of one of said longitudinal members and an adjustable bridging member between said switch contact elements.

2. An electrical heating device for curling tongs comprising a cylinder formed of material of relatively high temperature coefficient of expansion, a rod within and connected at one end to said cylinder formed of material of relatively low temperature coefficient of expansion, a heating resistance wound 20 upon said rod, a resiliently axially displaceable contact element at the free end of said rod and in series with said resistance, means for limiting the displacement of said contact element in one direction relatively to the rod 25 a resilient switch contact element at the free end of the cylinder in series with the resistance and an adjustable bridge intermediate of said switch contact elements.

3. An electrical heating device for curling tongs comprising a cylinder formed of material of relatively high temperature coefficient of expansion, a rod within and connected at one end to said cylinder formed of material of relatively low temperature coefficient of expansion, a heating resistance wound upon said rod, a resiliently axially displaceable contact element at the free end of said rod and in series with said resistance, means for limiting the displacement of said 35 contact element in one direction relatively to the rod, and a switch contact element at the free end of the cylinder in series with the resistance.

4. An electrical heating device for curling tongs and the like comprising a hollow cylindrical casing, an insulated contact mounted in one end of said casing, a rod having a lower temperature coefficient of expansion than said casing and being mounted at one 50 end within said casing and having its free end facing said insulated contact, a resilient contact element mounted on the free end of said rod and cooperating with said insulated contact, and a heating winding wound upon said rod within said casing and having its circuit completed through said contacts.

5. An electrical heating device for curling tongs and the like comprising a hollow cylindrical casing, an insulated contact mounted 55 in one end of said casing, a rod having a

lower temperature coefficient of expansion than said casing and being mounted at one end within said casing and having its free end facing said insulated contact, a resilient contact element mounted on the free end of said rod, an adjustable bridge connecting said contact elements, and a heating winding wound upon said rod and having its circuit completed through said contacts and bridge.

In testimony whereof I have hereunto 75 affixed my signature.

ALFRED REHM.
